(57) CLAIM

The ornamental design for a video conference camera, as shown and described.

DESCRIPTION

FIG. 1 is a top, front and left side perspective view of a video conference camera showing my new design;

FIG. 2 is a bottom, rear and right side perspective view thereof;

FIG. 3 is a front elevation view thereof;

FIG. 4 is a rear elevation view thereof;

FIG. 5 is an enlarged left side elevation view thereof;

FIG. 6 is an enlarged right side elevation view thereof;

FIG. 7 is a top plan view thereof; and,

FIG. 8 is a bottom plan view thereof.

The broken lines in the drawings illustrate portions of the video conference camera that form no part of the claimed design.
